(57) **CLAIM**

We claim the ornamental design for a combination kitchenware and spork, as shown and described.

DESCRIPTION

FIG. 1 is a perspective view of a combination kitchenware and spork, showing our new design;

FIG. 2 is a top plan view of FIG. 1;

FIG. 3 is a bottom plan view of FIG. 1;

FIG. 4 is a front elevational view of FIG. 1;

FIG. 5 is a rear elevational view of FIG. 1;

FIG. 6 is a right-side elevational view of FIG. 1; and,

FIG. 7 is a left-side elevational view of FIG. 1.

It is understood that the first and second embodiments have identical bottom plan views, and front, left side, right side, and rear elevational views, and that the third and fourth embodiments also have identical bottom plan views, and front, left side, right side, and rear elevational views.
